(57) **CLAIM**

We claim the ornamental design for a cartridge label, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top plan view of the first embodiment of a cartridge label showing our new design;
FIG. 2 is a top plan view of the second embodiment;
FIG. 3 is a top plan view of the third embodiment;
FIG. 4 is a top plan view of the fourth embodiment;
FIG. 5 is a top plan view of the fifth embodiment;
FIG. 6 is a top plan view of the sixth embodiment; and,
FIG. 7 is a top plan view of seventh embodiment thereof. The broken lines shown in the drawings illustrate portions of the cartridge label that form no part of the claimed design.
